UNITED STATES PATENT OFFICE.

WILLIAM H. DEWAR, OF PHILADELPHIA, PENNSYLVANIA, ASSIGNOR TO THE POOLEY COMPANY, OF PHILADELPHIA, PENNSYLVANIA, A CORPORATION OF PENNSYLVANIA.

RADIO GRAMOPHONE AMPLIFIER.

Application filed July 21, 1925. Serial No. 44,970

The invention relates to cabinets for containing a radio receiving outfit and a sound reproducing machine or gramophone.

The object of the invention is to provide means to contain the sound reproducer and record and also the radio outfit, associated with sound conveying and sound amplifying means communicating with both the gramophone sound reproducer and the radio loud speaker. In my invention, the sound conveying and amplifying means contains a partition dividing the same into two sound amplifiers communicating respectively with the gramophone sound reproducer and the radio loud speaker, said partition being movable to contract or enlarge the dimensions and decrease or increase the sound amplifying effect of either amplifier.

A preferred embodiment of the invention is shown in the accompanying drawings, in which—

Fig. 1 is a longitudinal section of a cabinet embodying my invention.

Fig. 2 is a front view of the upper part of the cabinet.

Fig. 3 is a vertical section on line 3—3 of Fig. 2.

The cabinet may be divided into any number of suitable compartments. As shown, a lower compartment *a* is provided for the radio batteries; a middle compartment *b* for the radio set *k*; and an upper compartment *c* for the motor-driven turn table *d* for the gramophone record, the pivoted tone arm *e* of the gramophone, and the sound amplifying means.

Depending from the floor of the upper compartment is a block *f*, which is hollowed out to form two gradually expanding sound-conveying channels or conduits *g* and *h*. Channel *g* communicates at its contracted end with the tone arm *e*. Channel *h* communicates at its contracted end with the expanded end of a metal sound conveyor *i*, the contracted end of the latter communicating with the loud speaker *j* of the radio.

In the rear of the upper compartment *c* is a block *m* hollowed out to form two short channels *g'* and *h'* which communicate respectively with, and form continuations respectively of, the two channels *g* and *h*.

Fixed within the upper compartment *c* is the top wall *n* and side walls *o* and *p* of a compound amplifying chamber. The top

wall *n* slopes upward from the block *m* above the sound conduit exits toward the upper front edge of the compartment. The side walls *o* and *p* diverge in their forward extensions. Thereby is formed an amplifying chamber whose dimensions, measuring laterally and vertically, increase from its rear sound entrance end to its front sound exit end.

A partition or shutter *r* divides the amplifying chamber into two amplifiers *s* and *t*, communicating respectively with channels *g'* and *h'*. The partition, at its rear, is pivoted on a vertical axis, and may be swung into such position that it extends forward parallel to the side walls of the cabinet, or it is swingable laterally in either direction, so as to contract either amplifier and at the same time expand the other. When moved, for example, to the right of its central position, it contracts amplifier *s* and expands amplifier *t*. Contracted amplifier *s* then has its side walls extending about parallel, but, owing to the inclination of the fixed upper wall *n*, its dimensions, vertically measured, expand gradually from rear to front, giving a minimum amplifying effect to sound from the gramophone. By swinging the partition *r* from this extreme position more or less toward the left, the amplifying effect of amplifier *s* may be increased as desired, the maximum amplifying effect being obtained when the partition is swung to the extreme left as shown in the drawing. Similarly, the amplifying effect on the sound from the radio loud speaker may be increased or diminished at will.

Having now fully described my invention, what I claim and desire to protect by Letters Patent is:

1. In a radio-gramophone cabinet, the combination with the turn table and pivoted tone arm of a gramophone, and the loud speaker unit of a radio set, of means providing sound conduits communicating respectively with said tone arm and loud speaker unit, the exit ends of said sound conduits being arranged side by side, and a compound amplifying chamber communicating with said sound conduit exits, said amplifying chamber comprising diverging walls arranged on opposite sides of said exits and extending at substantially the same angle relative to the center of the horn, and an

- intermediate partition extending from between said exits and dividing the amplifying chamber into two amplifiers communicating respectively with said two conduits, said 5 partition being swingable toward and from either wall and to a point substantially parallel with either wall to thereby contract either amplifier and simultaneously expand the other.
- 10 2. In a radio-gramophone cabinet, the combination with the turn table and pivoted tone arm of a gramophone, and the loud speaker unit of a radio set, of means providing sound conduits communicating respectively with said tone arm and loud speaker unit, the exit ends of said sound conduits being arranged side by side at a substantial distance back of the front of the cabinet, and 15 a compound amplifying chamber communi- cating with said sound conduit exits and 20 comprising a forwardly extending top wall sloping upward from above said exits, forwardly extending side walls diverging from opposite sides of said exits and extending at substantially the same angles on opposite 25 sides of the center of the amplifying chamber, and a swinging intermediate forwardly extending vertical partition the height of which gradually increases from rear to front and which is pivoted on a vertical axis between 30 said sound exits and arranged to be positioned substantially parallel with either side wall.
- 10 2. In a radio-gramophone cabinet, the combination with the turn table and pivoted tone arm of a gramophone, and the loud speaker unit of a radio set, of means providing sound conduits communicating respectively with said tone arm and loud speaker unit, the exit ends of said sound conduits being arranged side by side at a substantial distance back of the front of the cabinet, and 15 a compound amplifying chamber communi- cating with said sound conduit exits and 20 comprising a forwardly extending top wall sloping upward from above said exits, forwardly extending side walls diverging from opposite sides of said exits and extending at substantially the same angles on opposite 25 sides of the center of the amplifying chamber, and a swinging intermediate forwardly extending vertical partition the height of which gradually increases from rear to front and which is pivoted on a vertical axis between 30 said sound exits and arranged to be positioned substantially parallel with either side wall.
- In testimony of which invention, I have hereunto set my hand, at Philadelphia, 35 Pennsylvania, on this 20th day of July, 1925.

WILLIAM H. DEWAR.
